(57) **CLAIM**

The ornamental design for a box, as shown and described.

DESCRIPTION

FIG. 1 is a front right perspective view of a box showing my new design in a closed configuration.

FIG. 2 is a front elevational view thereof.

FIG. 3 is a rear elevational view thereof.

FIG. 4 is a left elevational view thereof.

FIG. 5 is a right elevational view thereof.

FIG. 6 is a top plan view thereof.

FIG. 7 is a bottom plan view thereof.

FIG. 8 is a front right perspective view of the box in a semi-open configuration.

FIG. 9 is a front elevational view thereof.

FIG. 10 is a rear elevational view thereof.

FIG. 11 is a left elevational view thereof.

FIG. 12 is a right elevational view thereof.

FIG. 13 is a top plan view thereof.

FIG. 14 is a bottom plan view thereof.

FIG. 15 is a front right perspective view of the box in an open configuration.

FIG. 16 is a front elevational view thereof.

FIG. 17 is a rear elevational view thereof.

FIG. 18 is a left elevational view thereof.

FIG. 19 is a right elevational view thereof.

(Continued)

FIG. 20 is a top plan view thereof; and,
FIG. 21 is a bottom plan view thereof.

The broken lines in the drawings depict portions of the box
that form no part of the claimed design.

1 Claim, 15 Drawing Sheets
